SLIVER DRAWING MECHANISM

Edmund E. Blake, Saco, Maine, assignor, by
mesne assignments, to Saco-Lowell Shops,
Biddeford, Maine, a corporation of Maine

Application October 29, 1936, Serial No. 108,191

2 Claims. (Cl. 19—133)

This invention relates to drawing mechanisms of the general type used in the preparation of slivers for spinning. While it will be herein disclosed in connection with a drawing mechanism designed more especially for use in handling cotton slivers, it will be understood that the invention is equally applicable to operation on slivers or rovings composed of other fibers.

Such mechanisms perform the functions of drawing the slivers in order to straighten the fibers and to dispose them in a more nearly parallel relationship to each other, which is essential in the best preparation of the sliver for spinning. In addition, these mechanisms attenuate the sliver to a size suitable for the spinning operation. A long draft in a given machine is of advantage in producing the desired results with as few operations and as little handling of the fibers as possible. It has been found that such a draft is facilitated by folding the moving sliver laterally upon itself at an intermediate point in the drawing operation and thus bringing the fibers at the selvages, which tend to stray in drafting, back into the line of flow of the main body of fibers being drafted and producing a sliver of approximately uniform cross-section. It has also been found that control of the fibers at the folding point is improved by guiding the sliver through a trumpet as it is fed to those drawing rolls which precede the folding operation.

In operating a machine organized in accordance with the foregoing, it was found that wear tended to become localized on the drawing rolls, particularly the covered top rolls, and this suggested the desirability of traversing the sliver with a view to distributing the wear. While this normally is a simple operation, it involves unusual problems in a drawing mechanism of the character just described because of the fact that the sliver is in the form of a flat ribbon from the time it passes through the first pair of rolls until it reaches the folding rolls. In addition, the drafting between any pairs of rolls is disturbed if, in any such zone, an attempt is made to move the ribbon laterally by forcing a member against the selvage of the ribbon.

A further difficulty found in attempting to traverse the sliver in any orthodox fashion was that both the trumpet and the folding rolls also had to be traversed, and in order to maintain the sliver in proper alignment with said rolls, it was necessary to give the trumpet considerable "lead" with reference to the rolls. In other words, as the traverse occurs in one direction,

5 the trumpet moves in advance of the rolls until the end of the traverse is reached, and then it pauses, waits for the rolls to catch up with it, and starts in the opposite direction ahead of the rolls. This necessarily involves complications which are undesirable.

The present invention satisfactorily deals with the conditions above described, and provides a thoroughly practical solution for the problems presented by them. Stated more specifically, the invention provides a thoroughly reliable traversing mechanism for handling a ribbon sliver in a drawing mechanism of the type above described and in which the control of the edge fibers is maintained practically as effectively as though the traversing motion were not used, which can be manufactured economically, and which will require a minimum of care and attention in operation.

20 The nature of the invention will be readily understood from the following description when read in connection with the accompanying drawings, and the novel features will be particularly pointed out in the appended claims.

25 In the drawings,

Figure 1 is a side elevation of portions of a drawing frame embodying features of this invention, some parts of the mechanism being broken away;

30 Fig. 2 is a vertical, sectional view, largely diagrammatic in character, but in general taken on the line 2—2, Fig. 1;

Fig. 3 is a plan view of the parts shown at the right-hand side of Fig. 1;

35 Fig. 4 is an end view of the eccentric strap illustrated in Fig. 3 and the parts immediately connected therewith;

Figs. 5 and 6 are sectional views, with parts in elevation, showing details of the traversing mechanism;

40 Fig. 7 is a diagrammatic, sectional view, on a larger scale, of the drawing mechanism shown in Figs. 1 and 2;

Fig. 8 is a rear elevation of the folding roll 45 illustrated in Fig. 7, showing the manner in which the sliver is fed to them;

Fig. 9 is a perspective view of a portion of a sliver illustrating certain of the effects of the operations which it goes through; and

50 Fig. 10 is a transverse, sectional view of the folded sliver.

Referring first to Fig. 7, it will be observed that the drawing mechanism there shown comprises upper and lower rear rolls 2 and 3, respectively, a second or intermediate pair of rolls 4 and 5,

upper and lower folding rolls 6 and 7, and upper and lower front rolls 8 and 9. The bottom rolls may be driven in the usual manner and the folding rolls are positively connected together through the gears 6a and 7a, Fig. 1. Immediately behind the first pair of rolls 2 and 3 is a trumpet 10 for guiding the sliver S into the bite of said rolls. The second pair of rolls 4 and 5 revolve at a higher peripheral speed than the rear rolls 2 and 3 in order to give the desired draft, and for the same reason the front rolls 8 and 9 revolve at a higher peripheral speed than do the folding rolls 6 and 7. Usually, however, a minimum draft occurs between the second pair of rolls and the folding rolls, the latter rolls running at a slightly higher peripheral speed, in order to pull the sliver into the folding roll definitely and under the desired control. This step in the feed of the sliver is utilized solely to perform the folding operation. Thus the drawing operation is divided into two steps and the fold is produced between these steps.

In the usual arrangement, all of the lower rolls are driven positively by gearing located at one end of the drawing frame, and the upper rolls are revolved solely due to their contact with their respective lower rolls, these upper rolls being made in sections which are removably supported for convenience in threading up, cleaning, and the like. The lower rolls may be either fluted or smooth, but the upper rolls customarily are smooth. Usually the upper rolls 2, 4 and 8 are covered, and saddles and weights are used with them to hold them downwardly against their respective lower rolls with the desired degree of pressure. As shown in Fig. 8, the upper folding roll preferably is grooved, while the lower roll 7 is made sufficiently thin to fit into the groove of the upper roll with only the clearance necessary for smooth running. It is desirable, also, to locate the two front pairs of rolls at a lower level than the two rear pairs in order to facilitate the folding operation. As a rule, the upper roll 6 is self-weighted.

The arrangement above described is known and has been used heretofore. In a drawing frame a series of units like that shown in Fig. 7 are arranged side by side with the lower rolls running from one end to the other of the frame and common to all the units, as illustrated in Figs. 1 and 3.

As above stated, it is desirable to traverse the sliver, and for this purpose it is necessary to traverse both the folding rolls and the trumpet. I have found that the difficulties above discussed in performing this operation can be avoided, and the necessity for "lead" of the trumpet traverse eliminated by traversing both the trumpet and the folding roll in unison, but at a very low rate. In other words, if this rate is made slow enough, then any necessity for "lead" is completely avoided. The desirable condition is to make the speed of traverse as fast as possible while maintaining the movement of the sliver from the trumpet to its cooperating pair of folding rolls in substantially a straight line lying at right angles to the direction of traverse. At least any angle in this path of travel should be so slight that it will not interfere with the feeding of the sliver properly into the folding rolls. To state this matter somewhat differently, the instantaneous component of this traversing movement should be so small that it will not interfere with the feeding operation just described. In practice the traversing period varies roughly from a com-

plete reciprocation in, say, four minutes to one in twice that period. While the latter limit can be greatly increased, there is always the danger of grooving the covered rolls if the sliver rests in one place long enough to overcome the elastic limit of the covering. Inasmuch as it is usually more convenient to drive the traversing mechanism from the lower rear roll 3 than from any other roll, and since the front roll speed necessarily is determined by the spindle speed while the back roll speed is varied to suit the requirements of the draft, it necessarily follows that the speed of this rear roll will vary greatly with different conditions. Consequently, the time occupied in making a complete traverse will vary.

A further condition encountered in traversing the folding rolls is that the upper roll is made up of disconnected sections so that it is impractical to traverse this roll directly. The lower folding roll, however, extends from one end to the other of the machine, although it may also be made of sections secured together, end to end. I have found, however, that it is entirely practical and greatly simplifies the traversing mechanism to traverse the upper roll through its engagement with the lower roll. In other words, if the lower folding roll is reciprocated longitudinally of its own axis, the upper folding roll will be compelled to move with it because of the nature of its engagement with the lower roll. However, there necessarily is some clearance between the opposite sides of the thin lower folding roll and the walls of the groove in its upper roll. Consequently, when the lower roll is being traversed rapidly in one direction, it crowds against one wall of said groove and all of the clearance is between its opposite side and the adjacent wall. There is a tendency for fibers to work into the crease or crevice so provided, and thus to produce a fuzzy edge on the folded sliver. The slow rate of traverse above described, however, not only avoids the problem of "lead," but also makes it possible to produce the traverse of the upper folding roll through its contact with the lower roll without accumulation of clearance at one side or the other of the groove. As above pointed out, the instantaneous lateral component of this traversing movement is practically zero so that it has no material effect on the running relationship of the folding rolls, and they are, therefore, continuously free to find their own running engagement almost as freely as they would if no traverse were employed. Consequently, with this arrangement there is no more tendency to disturb the selvage of the folded sliver than there would be if the traversing movement were absent. Thus this slow traverse solves two problems which have been exceedingly troublesome in a drawing mechanism of this type. At the same time it permits the use of a single traversing mechanism to operate both the trumpets and the folding rolls.

The mechanism at present preferred for producing this traversing motion is illustrated in Figs. 1 to 4, inclusive. Referring to them, it will be seen that the trumpets 10 for the entire series of units are rigidly secured to a bar 12 which is mounted to slide in a path parallel to, and immediately beside, the lower rear roll 3. Its right-hand end, Fig. 3, is secured in a holder 13 which, as best shown in Figs. 2 and 4, is pivoted to the upper end of a lever 14. This lever is fulcrumed on the machine frame at 15, Figs. 1 and 2, and a yoke 16 is secured rigidly, but adjustably, to it by means of a bolt 17. It straddles the end of

the lower folding roll shaft 1', and the upper ends of the two arms of this yoke are slotted to receive pins 18-18, Fig. 3, projecting laterally from a collar 20 which is held between two thrust bearing members 21-21, both of which are secured to the end 1' of the lower folding roll shaft. The arrangement is such that the shaft and the bearing members 21-21 can rotate freely relatively to the collar 20, but all of these parts are secured together for movement axially of the shaft. The pivots 18-18 are in line with the pivot 22 which connects the lever 14 with the trumpet bar 12. Consequently, if the lever 14 is rocked on its fulcrum 15, it will move both the bar 12 and the shaft 1' in a direction parallel to the drawing rolls and in unison with each other.

For the purpose of imparting this movement to the members 12 and 1' at the slow rate desired, an eccentric strap 24 is pivoted to the lever 14 at 25, this strap running on an eccentric 26 secured rigidly, but adjustably, to the shaft 27. A worm wheel 28, also fast on this shaft, is driven by a worm 30 on a vertical shaft 31, and the latter is connected through worm gears 32 and 33 with the lower rear drawing roll 3 which is driven by the usual gearing at the opposite end of the machine. Thus motion is transmitted positively from the roll 3 to the trumpet bar 12 and the lower folding roll shaft 1', and results in reciprocating these members in unison at a very slow rate, as above described.

The length of stroke of the reciprocating movement so imparted to the parts 1' and 12 can be conveniently adjusted by the arrangement shown in Figs. 4 and 6 for varying the throw of the eccentric strap. As shown in said figures, the eccentric 35 is adjustably secured to the shaft 27 by a set screw 36 and this eccentric fits within an eccentric bushing 26, these two parts being secured together by a set screw 37 to form a compound eccentric unit. Several notches 38, Fig. 4, are formed in the periphery of the eccentric 35 to receive the point of the set screw 37, and numbers are associated with the respective notches to designate the length of stroke that will be imparted to the trumpet rod and the lower folding roll by the relative adjustment of the parts 26 and 35 when the set screw is located in one or another of these notches. Such adjustment varies the degree of displacement of the center of the shaft 27 from the center of the eccentric strap 24, as will be evident from an inspection of Fig. 4.

The reciprocating movement imparted to the shaft 1' requires suitable provision for sliding movement of this shaft relatively to its driving gear at the left-hand end, Fig. 3, of the machine, and Fig. 5 illustrates a construction which can conveniently be used for this purpose. The driving

gear (not shown) meshes with a pinion 40 which preferably is integral with a bearing sleeve 41. Both these members are splined to the shaft 1' and the sleeve is mounted to revolve in a bearing member 42 which is secured to any convenient part of the machine frame. Thus the shaft can slide freely longitudinally of its own axis without disturbing its relationship to the parts that support and drive it.

Having thus described my invention, what I desire to claim as new is:

1. In a machine of the character described, the combination of a series of drawing units arranged side by side, each of said units including a plurality of pairs of drawing rolls arranged one in advance of another to feed and draw a sliver, each pair including an upper roll and a lower roll, a trumpet mounted in position to guide a sliver into the bite of the rearmost pair of said rolls, another pair of rolls located between adjacent pairs of said feeding and drawing rolls for folding the sliver as it passes from one of the latter pairs of rolls to the next, the lower rolls of said units being common to the series and being driven, a bar on which the trumpets for said units are secured, means supporting said bar for reciprocating motion in a direction parallel to said rolls, a lever mounted at one end of said series of units, a worm gear mechanism for rocking said lever, and means connecting one end of said lever with said bar and with the lower of said folding rolls to traverse said bar and said lower roll in unison.

2. In a machine of the character described, the combination of a series of drawing units arranged side by side, each of said units including a plurality of pairs of drawing rolls arranged one in advance of another to feed and draw a sliver, each pair including an upper roll and a lower roll, a trumpet mounted in position to guide a sliver into the bite of the rearmost pair of said rolls, another pair of rolls located between adjacent pairs of said feeding and drawing rolls for folding the sliver as it passes from one of the latter pairs of rolls to the next, the lower rolls of said units being common to the series and being driven, a bar on which the trumpets for said units are secured, means supporting said bar for reciprocating motion in a direction parallel to said rolls, a lever mounted at one end of said series of units, an eccentric strap connected with said lever to rock it, an eccentric for operating said strap, worm gearing driving said eccentric, an eccentric bushing encircling said eccentric and adjustable around it, and means connecting said lever with said bar and with the lower of said folding rolls to traverse said bar and lower roll in unison.

EDMUND E. BLAKE.
